HEATING UNIT

Pilade Leoni, Providence, R. I., assignor to Lemur, Incorporated, Providence, R. I., a corporation of Rhode Island

Application February 25, 1937, Serial No. 127,625

2 Claims. (Cl. 122—45)

This is a new and useful improvement relating to a mechanical and physical arrangement for the better recovery of the heat generated through the combustion of fuel for the purpose of heating water or other liquid medium to generate steam, or for other uses to which this improvement may adapt itself.

The chief object of my improvement makes for a greater elimination of heat losses in the process of heat transfer to a medium to be heated. The semi-flash production of steam in a boiler is another object. A further object of this improvement is the application of the heat generated through the combustion of fuel, first to the upper levels of the liquid medium to be heated and then successively to the subsequent lower strata of said liquid medium.

Other advantages and other objects of my improvement may be more apparent from consideration of the details described and claimed.

With references to the drawings,

Figure 1 is a vertical section of the boiler taken along line C—C of Figure 2, and showing a part of the lower casing broken away.

Figure 2 is an end view of the upper part of the boiler section taken along line B—B of Figure 1, and shows the arrangement of heat conduits 20 and 21.

Figure 3 is a vertical section of Figure 2 taken along line A—A of Figure 2 and shows the arrangement of the heat passages or conduits on each side of the combustion chamber.

Figure 4 is a general view of the assembled sections of the boiler with the gas burner's rings 28 and 29 in position at the inlet 6 of the combustion chamber 5.

Referring to the drawings in detail, Figure 1 shows in section the three parts composing the boiler. The first section being the steam dome 1 formed by outer shell 2 and being equipped with steam port 17, gauge port 14a, safety valve port 16, and a flange 3. Flange 3 is bolted to the next lower section of the boiler by bolts 11.

The second section of the boiler is formed by an outer shell 4, a combustion chamber 5 enclosed within said shell 4, and having its inlet 6 to the atmosphere, and outlets 7 and 7a, to which are connected heat passages or conduits 20 and 21. The outer shell 4 is equipped with upper flange 8 and lower flange 9 which are bolted to the adjoining flanges of the upper and lower section of the boiler by bolts 11 and 11a.

The third section of the boiler is formed by outer shell 12 and the inner shell 19. Inner shell 19 is closed at the top and opened at the

bottom, and the lower edge of the outside shell 12, and inner shell 19 are bonded together to form the bottom of an annular tank 18 into which, in subsequent lower circular layers, are placed heat passages or conduits 20 and 21 which fill the intervening space between tank 19 and tank 12 to the extent needed to leave only room enough for a film of water to rise on all sides of said heat conduits. Said heat passages or conduits have their upper ends connected to the outlets 10 and 7a of the combustion chamber 5, and have their lower ends protruding at the bottom of shell 12 and connected to the inlet 22 of a suction device 24 placed near the bottom outside of the boiler. Outlet 25 of suction device 24 discharges into a stack not shown, and is equipped with a drain 26. The annular tank 18 is provided with ports 14 for gauge and other attachments, port 13 for the return of the condensed steam into said tank, and port 15 for the feed of liquid to 20 said tank.

The liquid to be heated, as contained by said boiler unit, is kept within the boiler at such level as to barely submerge the combustion chamber and the heating conduits.

The combustion chamber 5 and the heat passages or conduits 20 and 21 fill as much of the space which is surrounded by shell 4 as it is possible, but leaving just enough of it to allow a continuous film of water to rise to the surface so as to replace the water evaporated in making steam, and so as to maintain constant the level of the water in the boiler.

The operation of the boiler thus far described is as follows:

The boiler is filled with the liquid to be heated up to a level sufficient merely to submerge the combustion chamber 5 and heat passages or conduits 20 and 21. Suction device 24 is then put into operation and creates a vacuum inside the 40 heat passages or conduits 20 and 21 and combustion chamber 5. Fuel is now admitted through inlet 6 into combustion chamber 5 and there combusted. The heat thus generated together with the products of the combustion are then carried away through outlets 7 and 7a of the combustion chamber 5 into and through the heat passages or conduits 20 and 21 to the suction device 24 and then through its outlet 25 into the stack not shown.

Inasmuch as the combustion chamber 5 and the upper portions of heat passages or conduits 20 and 21 are immersed just below the very top surface of the liquid to be heated, it follows that the most intense heat generated through the 55

combustion of fuel, is in direct contact, first, with the top levels of the liquid, and successively with the subsequent lower levels of said liquid. This effects the most prompt and efficient transfer of heat to the liquid surrounding the combustion chamber 5 and the heat passages or conduits 20 and 21, because the temperature of the liquid and the temperature of the above mentioned parts are divergent, that is: the heat, on its travels from the combustion chamber through and along the heat conduits 20 and 21 to the lower levels of the liquid, always meets subsequent lower temperatures of said liquid.

Having thus described the nature and objects of my improvement and a preferred embodiment of the same, which embodiment is to be taken as illustrative rather than limitative, what I desire to secure by Letters Patent is:

1. A boiler unit comprising, in combination, 20 a top section, a mid-section and a lower section; all said sections being connected for water flow from the lower section to the top section; the top section including a steam chamber; the mid-section enclosing within its walls a combustion chamber having its outlet connected to conduits coiled partly within the said mid-section and partly within the said lower section; and the lower section being composed of an inner circular shell closed at the top and of a larger outer circular shell the lower edge of which is bonded with the lower edge of the smaller shell to form an annular

tank into which the said heat conduits descending from the combustion chamber in the mid-section are coiled into successively lower layers, said heat conduits having their lower ends passing through the wall of the lower part of the outer shell. 5

2. A boiler unit comprising, in combination, a top section, a mid-section and a lower section; all said sections being connected for water flow from the lower section to the top section; the top section including a steam chamber; the mid-section enclosing within its walls a combustion chamber having its outlet connected to conduits coiled partly within the said mid-section and partly within the said lower section; and the lower section being composed of an inner circular shell closed at the top and of a larger outer circular shell the lower edge of which is bonded with the lower edge of the smaller shell to form an annular tank into which the said heat conduits descending from the combustion chamber in the mid-section are coiled into successively lower layers, said heat conduits having their lower ends passing through the wall of the lower part of the outer shell; the said heat conduits substantially filling the sand tank whereby the flow of water from the lower section to the top section is so restricted as to substantially replace the water converted into steam in the top section. 10 15 20 25
